UNITED STATES PATENT OFFICE.

BRUNO QUAST, OF COLOGNE-DEUTZ, GERMANY.

CONTINUOUS ROLLING-MILL.

1,271,361.

Specification of Letters Patent. Patented July 2, 1918.

Application filed March 9, 1916. Serial No. 221,572.

To all whom it may concern:

Be it known that I, BRUNO QUAST, a subject of the King of Prussia, German Emperor, residing at No. 9 Reischplatz, Cologne-
5 Deutz-on-the-Rhine, Rhenish Prussia, Germany, have invented certain new and useful Improvements in Continuous Rolling-Mills, of which the following is a specification.

My invention relates to improvements in 10 rolling mills and it has for its objects among others to provide a simplified form of continuous rolling mill in which all pairs of rollers or cylinders are driven from a common gear to roll the metal in a forward and 15 backward direction, said pairs of rollers or cylinders being placed behind each other and driven with an increasing circumferential speed. Two or more pairs of rollers are juxtaposed and connected by a common driving gear so that each group of rollers will 20 roll in one direction only, either forward or backward, without reversing the driving gear or the motion of the driven pairs of rollers.

25 The present invention has for a further object to reduce the number of pairs of rollers required in a continuous rolling mill of the kind heretofore employed and thereby simultaneously simplifying the driving 30 means and materially increasing the output of the mill. I attain this object by rolling the blocks or blooms in the reverse direction in a continuous rolling train having two or more groups of pairs of rollers juxtaposed 35 and following each other in succession, the reversal of motion being obtained without necessitating the lifting of the blocks or blooms from one pair of rollers and depositing the same into the following group. The 40 several groups of pairs of rollers are so arranged that the driving wheels serving to impart motion to the rollers alternately serve as intermediate wheels.

45 Other objects and advantages of the invention will hereinafter appear and the novel features thereof will be particularly pointed out in the appended claims.

50 The invention is clearly illustrated in the accompanying drawings, which, with the characters of reference marked thereon, form a part of this specification, and in which—

Figure 1 is a side elevation of the rolling train.

55 Fig. 2 is a plan of the same.

Like reference characters refer to like parts in both views.

Referring to the drawings,—

The four pairs of rollers a' , a^2 , a^3 and a^4 receive motion by the four driving members 60 b' , b^2 , b^3 and b^4 , the rollers a' and a^2 forming the first group and the other rollers a^3 and a^4 the second group, the latter being arranged out of line with relation to the first group. The four driving frames or members b' , b^2 , b^3 and b^4 constitute a single group, the same being coupled or geared by the gears c' , c^2 , c^3 and c^4 , all of which are fixed to the extensions of the driving shafts. By thus disposing the one group out of 70 alinement with the other, I provide that the driving wheels of one group alternately shall serve as intermediate wheels of the other group. The second group a^3 and a^4 will then turn in the opposite direction to 75 the rollers a' , a^2 of the first group, that is if the one group is turning away from the furnace the other group will turn toward the furnace. The roll blooms or blocks, therefore, being rolled to and fro, first passing 80 the rollers of one group, and then being rolled back by the rollers of the second group and so on, will be treated until the desired definite cross section is obtained. On entering into the rollers of each group, 85 the pressure of the rollers on the blooms, that is the coefficient of reduction, is independent of the circumferential speed of the pairs of rollers.

f' , f^2 are cross transporting rods.

The driving power preferably starts from the shafts by the aid of a fly wheel and the mode of conveying the bloom from one rolling group to the other by these rods will be evident. By my improvement I require only 90 four pairs of rollers to perform the same work as heretofore has required ten rollers, the block being rolled three times on the first group and twice on the second group of rollers. It further should be noted that according to my invention, two blocks or 95 blooms can be rolled at the same time, each in one group, without disturbing the continuous working order.

It will be noted that by my improvement 100 each block or bloom on changing from one pair of rollers to another pair, enters the second pair with its opposite end in contradistinction to entering with the same end, as heretofore.

What is claimed as new is:—

1. A continuous rolling mill comprising two or more juxtaposed groups of rollers arranged in overlapping relation in pairs placed behind each other, said groups being so arranged with relation to each other that the driving wheels controlling the rollers alternately serve as intermediate wheels.
2. A continuous rolling mill, comprising a plurality of juxtaposed groups of rollers ar-

ranged in overlapping relation in pairs placed behind each other, each pair of rollers turning only in one direction, thereby rolling the blocks or blooms alternately to and fro, each block on changing from one 15 pair of rollers to another entering the latter with its opposite end.

In testimony whereof I affix my signature.

BRUNO QUAST.
